VAPORIZER AND FUELIZER FOR INTERNAL-COMBUSTION ENGINES

Application filed June 13, 1924, Serial No. 719,723. Renewed May 9, 1929.

This invention relates to internal combustion engine fuel preparation, and more especially to vaporizer and fuelizer for internal combustion engines.

5 It is the especial object of this invention to provide means for the correct vaporization of modern gas engine fuel.

The present day gasoline, so-called, is in reality, a mixture of many different kinds of oil. These components vary in specific gravity and vaporizing temperature and in fact, in almost every characteristic which it is possible to vary. The problem of atomizing fuel and of providing a fuel to the engine cylinders 10 which will be near enough to a vapor to burn, is one which has received the attention of many inventors, and which it seems practically impossible to solve from mere changes or additions to the carburetor. As can be 15 readily appreciated, a single nozzle or a series of jets called upon to handle at one and the same time a mixture of oils ranging from light gasoline to heavy fuel oil can hardly be expected to produce an ideal mixture. Mani-

20 festly, some of the components will be completely atomized and reduced to fine drops while others will be discharged in comparatively large globules. It has been proven that such globules are the cause of crank case 25 oil dilution and the source of most carbon troubles now so prevalent in engines of this character. Devices have been produced which apply heat to the mixture leaving the carburetor jet with the idea of evaporating all 30 of the fuel components. These have not operated satisfactorily since the tars and the like resulting from the distillation of the heavier "ends" simply burn upon the heating surface, depositing carbon until the device is 35 rendered inoperative.

The herein disclosed invention provides means whereby the before-mentioned heavy globules are removed from the vapor stream, are heated to drive off the lighter components and whereby the heavier components 45 are removed from the heating surface before reaching a burning temperature, for re-combination with light components to be again atomized. The action of atomization is, of course, mechanical, heavy ends can be va-

porized and burned exactly as well as the lighter components if they can be broken up small enough. This invention provides for the recirculation and reatomization of the heavy ends until broken up in sufficiently 55 fine particles to mix with air, and to form a true vaporous mixture for engine fuel.

It is a further object of this invention to provide means whereby the heavier components and the larger globules will be first extracted from the gas stream, that these heavier liquids may first reach the coolest portion of the heating surface and may, at the same time, have the longest path to travel before 60 final discharge. It is also the purpose of this 65 invention to provide means for so equalizing pressures between the separator and the atmosphere or fuel supply that discharge may be effected from the separating device, irrespective of manifold or gasoline tank pressures, automatically and continuously, uninfluenced by other automobile or engine mechanism.

That embodiment of my invention which is shown in the appended drawings will serve 75 to present a form of apparatus which is adapted to perform the steps in my process and the description herewith will serve to make clear the means of accomplishing it. While this is a preferred embodiment of my 80 invention, it will be understood that many other forms of apparatus may be used with results of a beneficial nature.

Fig. 1 is a cross-sectional elevation in that embodiment, especially adapted for vertical 85 arrangement.

Fig. 2 is a cross-sectional elevation of my device in a preferred embodiment for horizontal arrangement.

Fig. 3 is a cross-sectional view of the valve mechanism shown in Fig. 2, taken upon the line 3—3 showing a second valve position.

Fig. 4 is a cross-sectional view of the valve mechanism shown in Fig. 2, taken upon the line 3—3, showing a third valve position.

Fig. 5 is an external elevation of the device shown in Fig. 2, as applied to an internal combustion engine and having a preferred form of fuel discharger or trap attached thereto, 100

said trap being shown in section to disclose the internal mechanism thereof.

Fig. 6 is a plan view of a detail of the valve mechanism and is taken upon line 6—6 of Fig. 5.

Referring first to Fig. 1, the intake manifold of the engine is indicated at 10, the exhaust manifold at 12, and the carburetor connection at 14, it being understood that these three may assume any of the various forms well known to those skilled in the art.

The carburetor may assume any of the forms adapted to atomization of fuel and for the mixture therewith with air to form a porous or gaseous mixture which for the sake of simplicity herein will be referred to in the following pages as a gas. In this particular form the carburetor connection 14, is shown as being above the intake manifold 10, but it will be understood that these parts may be reversed as to elevation.

The body of my device consists of a hollow casting 20, having a connection 22 with the engine exhaust 12. This connection 22 is preferably arranged opposite the exhaust from one of the engine cylinders, the velocity of the escaping gas having been found all that is necessary to provide a circulation of hot gases within the casting 20. However, it will be evident that casting 20 may be provided with a second opening or vent to assist in producing a circulation of the hot exhaust gases. Casting 20 has an upper head 24 secured thereto by such means as the screws 26 and a lower head 28, forming a collection chamber 30, for purposes which will be hereinafter described.

Clamped between heads 24 and 28 and the casting 20 is a tubular wall 32. Wall 32 is best made with corrugations 34, which serve the dual purpose of increasing the heating surface exposed to the exhaust gases within the casting 20 and to direct liquid downwardly to the chamber 30. Within the wall 32 is secured a spiral or worm member 38, while adjacent the lower end of the corrugations 34, but slightly separated therefrom is a receiving nozzle 40, communicating with and forming a part of the connection 10^a of the intake manifold 10. A chamber 30 is provided with a drain 42 which may be connected through a loop or liquid seal, trap or like device, to the carburetor fuel supply chamber or to the fuel tank. A preferred form of such trap is shown in Fig. 5.

The separator here shown (Fig. 5) is of the horizontal type which will be hereinafter described, but it will be understood that the trap is equally applicable to the vertical form of separator by a slight modification in piping connections.

The trap consists of a body 70 closed at its top by such means as a removable cover 72, secured to body 70 by the threaded studs 73, engaging the body flange 74. At its bottom

body 70 preferably tapers inwardly as at 75, to engage a threaded fitting 76, which in turn receives a screw plug 77. A gasket 78 being preferably employed to effect a liquid tight joint. Screw plug 77 connects through such means as the male threaded portion 79, with the gasoline tank, or with the fuel supply line to the carburetor, or to any other suitable point of discharge. Screw plug 77 is also provided with a vertical projection 80, having an internal passageway 81, terminating at its top in a chamber 82, closed by plug 83. Chamber 82 also communicates thru ball check valve 84 and passage 85 with the interior of body 70. Thus it will be seen that given an equal pressure in the body 70 and in the passage 81, liquid within the body and above chamber 82 will be discharged thru passage 81 by gravity.

Body 70 is also provided with a side bushing 87 which serves as a seat for a flap check valve 89, guided and supported by studs 90. Member 87 serves as a connection for a continuation of the drain 42 of the separator. It will therefore be seen that when the pressure within body 70 is the same as that within the separator, the separated fuel components will discharge thru drain 42 and valve 89 into body 70, and that when the pressure in the separator is lower than that in body 70 valve 89 will be held closed, preventing return flow to the separator. As will be understood, separator and intake manifold usually operate at considerably less than atmospheric pressure. It is therefore necessary, if the separated liquids are to be continuously removed thru the body 70, that means be provided whereby the pressure in body 70 is at times the same as that in the separator, so that liquids will be drained therefrom and at other times, the same as that pressure existing in the fuel tank or other point of discharge for the liquid deposited in body 70. To effect this necessary pressure change, automatically, I have provided a float 92, which is actuated by the accumulated discharge from the separator. Float 92, thru rod 93, and lever 94, actuates a connecting rod 95, which further actuates a double lever 97 fulcrumed upon the pin 99 of the standard 100, secured to the cover 72. A second standard, 102, projecting downward from cover 72 provides a fulcrum 103, for the lever 94 and a guide 105, for the connecting rod 95. Also secured to cover 72 is a further projection 107, which provides a pivot point 108 for the valve actuating lever 110.

Lever 110 thru a yoked stem 112 actuates a valve 114, controlling an equalizer connection 115, communicating with the interior of the separator and intake manifold. Lever 110 also controls the operation of a vent valve 120, which has a stem 121, provided with tappets 122, which allow a certain amount of lost motion, but which contact with lever 110 near

the ends of its stroke to actuate the vent. At the end furthest from the fulcrum 108, lever 110 is provided with a cross bar 125, to whose ends are secured springs 127, connected with a further cross bar 128, carried between the two arms of the double lever 97.

The operation of this valve gear is as follows: Assuming the float to be in its lowest condition, as would be the case when body 70 is empty, thru lever 94 and rod 95, double lever 97 is held in its lowest position. The cross-bar 128 is, therefore, below fulcrum 108 of the valve lever and the springs 127 draw this lever downward, opening the equalizing connection 115, thru the valve 114, and thru tappet 122, stem 121, and valve 120, closing the vent to the body 70. Manifestly, since the equalizer connection 115 is open to the separator the pressure within the body 70 will be the same as that in the separator, and the separated liquids will be free to flow downward thru connection 42 to the body 70. As the liquid rises within body 70, float 92 is lifted until cross bar 128 rises above the level of fulcrum 108 and the valve lever centre. Springs 127 now exert an upward pull upon the lever 110 and lift it with a snap action to its highest position, closing valve 114 and opening vent 120. The opening of vent 120 admits air to the body 70 and the suction in drain connection 42 closes valve 89. The head of liquid within body 70 has now been relieved of the intake vacuum and is free to lift the ball check 84 and to discharge to the fuel tank. The discharge of this liquid lowers float 92 and the cross bar 128 until it is again below fulcrum 108, when the valve lever snaps back to its original position, opening the equalizer 115, closing the vent valve 120, and permitting valve 89 to again reopen. This cycle of operations is repeated as often as may be necessary to discharge the liquids removed from the gas stream by the separator. Manifestly, this trap will operate regardless of the degree of vacuum within the intake manifold and without regard or dependence upon engine operation. In the event that a pressure fuel tank is employed vent valve 120 may be connected thru suitable piping to the tank and transfer will be effected exactly the same as though operating at atmospheric pressures.

It will also be clearly seen that in the event that the trap must be located below the fuel tank in order to receive the liquid from the separator, this trap may discharge to the carburetor float chamber or may be supplied through vent 120 with air or gas under pressure, from any suitable source, so that the opening of the valve 120 will apply pressure to the liquid contained in body 70, and force it upward against any desired head.

The preferred form of trap, which has just been described is particularly suited to my purposes, and it will be seen that its combina-

tion with a separator means herein described, forms a self-operative and entirely automatic system whereby the engine fuel vapor is automatically purged of unatomized and of partially atomized fuel, which is returned without substantial accumulation and as a part of a continuous process to the unatomized fuel for reatomization after dilution and re-admixiture.

The bottom of body 70, below the passage way 85 forms a convenient sediment chamber for the reception of any solid matter not readily dissolvable in new fuel. This chamber may be easily and quickly cleaned out by the removal of plug 77.

In some cases, I have found it convenient to dispense with the trap mechanism which has just been described and to connect drain 42 directly with an auxiliary atomizer in the form of a Venturi throat 44, connecting thru the tube 46 with a carburetor connection 14. Projecting upwardly into throat 44 is a tube 48, controlled by a cock 50, having a handle 52. Tube 48 may thus be opened to the exterior air to provide a blast sweeping throat 44 and assisting atomization therein.

The operation of this device is, briefly, as follows: Assuming that the engine is starting from a cold condition all of the parts, are, of course at the temperature of the surrounding atmosphere. The movement of the pistons produces a partial vacuum in the intake manifold 10, drawing in mixture from the carburetor, thru the connection 14. As this mixture passes downward as indicated by the arrows, worm 38 imparts a whirling motion to the gas and the heavier particles or globules, which have not been broken up by the carburetor, are thrown outward to be caught by the corrugations 34 of the wall 32 and directed downwardly to the chamber 30. The gas then passes thru the nozzle 40 into the intake manifold. Nozzle 40 is also preferably provided with openings 41, which serve to reduce the pressure within chamber 30 and to circulate a small portion of the gas mixture therethru. The liquid drained to chamber 30 passes out thru drain 42 for re-atomization in the throat 44.

As the engine starts to fire and exhaust gases are discharged from the cylinders to the exhaust manifold 12, hot gases are driven into the casting 20 and heat the wall 32. As this wall 32 becomes warm, the heavy liquid particles thrown against it are partially volatilized by the heat and their lighter components are driven off to be swept onward with the vapor stream to the engine. It should be understood, however, that while these heavier liquids are being subjected to the heat conveyed thru the walls 32, they are at the same time moving downward toward the chamber 30, under the impulse of the gas stream and of gravity. Thus heat is never supplied so rapidly as to completely

evaporate the heavy components and the tarry ingredients are not burned upon the heating surface, no matter how hot it may become. In other words, the process is a continuous one rather than periodic, as is the case with the ordinary hot spot devices, so-called. As has been previously stated the liquids from the chamber 30 may be remixed with fresh fuel for dilution, and reatomized in the carburetor or may be atomized by means of an air or hot gas blast from the tube 48 in the throat 44.

Referring now in particular to the horizontal form of my device as illustrated in Fig. 2, the casting 20 will be seen to be provided with heads 24^a and 28^a, very similar to the heads described in connection with Fig. 1. The inner wall 62 differs from the wall 32 in that its corrugations are preferably circumferential rather than longitudinal and are connected by means of a single longitudinal groove 61, so that the corrugations drain naturally to the chamber 30^a, similar in purpose to the chamber 30, already described. In this form I found it convenient to combine the Venturi throat with the carburetor connection 14, and to connect the drain 42^a by means of a pipe connection 62 to the Venturi reatomizer.

Cock 50^a is preferably of the three-way type, being provided with an atmospheric connection 64, and with a connection 66, which may communicate with an air heater and therethru to the atmosphere, or may communicate with the exhaust passages so that a hot blast may be drawn thru the tube 48 to atomize the liquid in throat 44. The cock 50^a is controlled by a handle 52, and when in the position shown in Fig. 2, a hot blast 40 is delivered to the reatomizer. When the cock is in the position shown in Fig. 3, no blast is provided in the tube 48, and atomization is caused entirely by the action of throat 44. When cock 50^a is in its third position, that shown in Fig. 4, air is drawn thru the connection 64 directly from the atmosphere. It will be understood that a suitable cock may be introduced in the connection 62 whereby liquid from chamber 30 may be directed to the fuel tank or carburetor or to the reatomizer as desired; the dotted lines 70 will illustrate the possible arrangement of such a cock.

The operation of the horizontal form of device is very similar to that described for the vertical one. Gas enters thru the carburetor connection 14, a whirling motion is imparted by the worm 38, the heavy globules are caught by the corrugated wall 60, directed 60 downwardly to the longitudinal groove 61, thence to the chamber 30^a, and out to the drain connection 42^a for recombination with fresh fuel and reatomization or for direct reatomization as has already been described. Nozzle 40^a differs from nozzle 40 in detail,

a Venturi shape being provided, the function is however identical.

It is desired to emphasize the fact that the herein disclosed device is a continuously operative and operating system, the heavier ends of the fuel are continuously and automatically taken care of over such period as the engine operates. Usually such devices are totally inoperative when no heat is supplied thereto. Such is not the case in this present device, the heavy components are taken care of irrespective of the engine temperature, are not overheated, and are not lost because of temperatures lower than those suited for economical engine operation.

It will, of course, be manifest that while the structure which has been shown is that preferred for the accomplishment of my process of treating engine fuels to provide a truly gaseous combustible mixture to the engine cylinder. Clearly, many alterations in the structure may be made without departing from the scope of my invention, as for instance, the centrifugal separation of the globules; any form of separation will serve for the production of beneficial results. The same is true of the method and means of heating and of reatomization. It will also be clear that many other changes may be made in the elements of my combination and in the complete combination without departing from the spirit of my invention and the scope of the appended claims.

What I claim is:

1. A continuously operative process for treating internal combustion engine fuels comprising, atomizing the liquid fuel, mixing air therewith to form a predetermined fuel mixture, imparting rotary motion to the air and atomized fuel mixture to force the larger liquid particles therefrom, arresting the liquid particles so forced and applying heat thereto as arrested and before collection, then collecting particles unvolatilized by the said heat application removing such component particles from the point of collection and altering their pressure to that of the original fuel before atomization, then remixing the component particles so removed with the liquid fuel before primary atomization to form a new fuel liquid and feeding same for atomization.

2. In a device for treating the heavy ends of internal combustion engine fuel, means between the fuel atomizer and the engine comprising a spiral gas passage, a corrugated surface surrounding said passage, and forming the outer wall thereof, an exhaust gas chamber surrounding said corrugated surface and supplying heat thereto, means adjacent the end of said passage for receiving vapors from said surface and from said gas passage, receiving means surrounding said vapor reception means for the collection of liquid drained from said corrugated surface and

further means for recirculation and reatomization of said liquid.

3. In a device for treating the heavy ends of internal combustion engine fuel, a combination of an exhaust gas chamber, a fuel vapor duct wall within said chamber extending therethrough and having its outer surface exposed to the exhaust gases therein, a centrifugal separating mechanism including a spiral vane mounted within said duct and discharging liquids to the wall thereof, and a separated liquid collection chamber at the end of said wall, and an automatic discharge device including valves and operating mechanism therefor, said exhaust gas chamber serving to heat said duct wall, said separating mechanism serving to deflect large liquid particles from the duct vapor to the aforesaid heated wall, said heated wall serving to drive off the readily volatilized components of said liquid, said collecting chamber serving to direct the unvolatilized components to said discharge device, whereby they are mechanically relieved of intake pressures and automatically discharged without accumulation.

4. In a fuelizer for internal combustion engines, means in the intake manifold for separating out the condensed liquid particles of fuel from the gaseous fuel stream, and means for rendering the first said means continuously operative comprising a closed body provided with a bottom discharge, controlled by an outwardly opened check valve, with a side inlet from said separator also provided with a check valve, with an equalizer connection to said separator, with a vent valve, and with a connecting valve gear controlling said equalizer and vent valve and operated by a float within said body whereby the rise and fall of liquid within said body controls conditions therein and liquid discharge thereto and therefrom for continuous operation.

5. In a fuelizer for internal combustion engines, a centrifugal separator inserted between the engine carburetor and the engine, said separator comprising an inlet discharging to a spiral baffle arranged within a tubular corrugated wall surrounded by a heating chamber connected with the engine exhaust, said wall terminating at one end in a chamber surrounding an outlet nozzle and provided with a discharge for fuel components thrown outward to said wall by the rotary motion imparted to the vapor from said carburetor by said spiral baffle and not volatilized by the wall heat.

6. In a fuelizer for internal combustion engines, a separator substantially as set forth in claim 5 in combination with a discharge trap connected to the chamber discharge and comprising a trap body connected to said separator discharge and having an inwardly opening inlet valve over such connection, said body also provided with a discharge out-

let having an outwardly opening check valve therein and with an equalizing connection to said separator and a vent to the atmosphere, said equalizing connection and vent provided with valves, a valve gear for said equalizing and vent valves and a float attached thereto responding to the liquid level within said trap body to actuate therefrom the said equalizing and vent valves to control the pressure within said body whereby the operation of the said valves in the trap inlet and discharge is effected and liquid removed from said separator to the atmosphere unaffected by pressure differences therebetween.

7. In a vaporizer and fuelizer for internal combustion engines, a body casing having removable end heads, a tubular corrugated wall having each of its ends clamped to one of the said heads in registry with an opening therein, an inlet nozzle mounted in one of said heads and projecting inwardly therefrom into said tubular wall whereby an annular chamber adjacent said head and opening to said tubular wall interior but out of the vapor stream is provided, a drain leading from said chamber for liquids deposited therein, a bypass tube leading from said drain around said tubular wall, a Venturi throat in said tube and an atomizing jet discharging to the inlet of said venturi, and spiral worm mounted within said tubular wall beyond said vapor nozzle.

Signed at Dallas, in the county of Dallas and State of Texas, this 3rd day of June, A. D. 1924.

RICHARD FREDERICK GILDEHAUS, Jr.
